UNITED STATES PATENT OFFICE

2,483,876

PHOTOMETRIC APPARATUS

William J. Boyer, Baltimore, Md.

Application January 21, 1947, Serial No. 723,246

9 Claims. (Cl. 250—236)

1

This application is a continuation in part of my co-pending application for Letters Patent of the United States, Serial No. 693,701, filed August 29, 1946, and entitled Colorimeter. The present invention has broad application to the field of optics and more particularly concerns an extremely simple optical colorimeter for rapid chemical analysis and generally allied purposes. Illustratively, it is admirably suited for sulfur or carbon determination in the manufacture of steel.

An object of my invention is to provide a colorimeter assembly which at once is simple, rugged, of low first cost, both in initial production and in operational maintenance, in which high intensity scanning means is employed with maintained constancy of transmitted light giving rise to highly sensitive and readily reproducible results, and which is entirely capable of satisfactory operation by a laboratory technician of but routine skill.

Another object is to provide a new colorimeter assembly of the general type described in which I employ means for cooling the source of light with entire satisfaction, maintaining constant operating temperature of the filter system employed as part of the colorimeter assembly, and in which the assembly can be adapted with but short lapse of time for analysis of solutions of various compositions.

Yet another object is to provide a water-jacketed colorimeter in which the filter assembly is mechanically separate from the water jacket, yet is in direct thermal association therewith.

Other objects and advantages will in part be obvious and in part more fully pointed out hereinafter during the course of the following description, taken in the light of the accompanying drawings.

My invention accordingly resides in the several parts, elements and features of construction, as well as in the relation of each of the same with one or more of the others, the scope of the application of all of which is more fully set forth in the claims at the end of this specification.

In the several views of the drawings, wherein I have disclosed that embodiment of my invention which I prefer at present,

Figure 1 comprises an exploded perspective view illustrating the various parts of my new assembly, cover members, together with the glass absorption cell, being removed in order to disclose more fully the exact details of the assembly;

Figure 2 is a side elevation, and Figure 3 is a corresponding longitudinal vertical section through the construction according to Figure 1.

2

Throughout the several views of the drawings, like reference characters denote like parts.

As conducive to a more precise understanding of my invention, it may be noted at this point that need has long been recognized in many industries, as for example in the steel foundry, for the rapid determination of certain elements such as carbon, sulfur and the like, which are ordinarily present only in traces. Thus, for example, it is important that rapid determination be achieved of the concentration of detrimental impurities; while it is equally important to determine the concentration of significant alloying additives. Various techniques have been evolved in an effort to accomplish this desired objective, some meeting with substantial success, others being only partially satisfactory, while some have proved to be of no practical utility. This is due in large measure to the fact that in present day high-speed production requirements, only short time intervals are available for analysis.

My present invention, therefore, has the important objective of producing a simplified colorimeter assembly which, while of low cost and of ready operation, gives rise to rapid, accurate, sensitive and readily reproducible results, for quantitative analysis of test specimens of given qualitative composition; and in which assembly both the light source and the color filter or filters which are employed are maintained at substantially constant temperature throughout the period of use.

My new colorimeter may be considered generally as comprising a compact, unitary assembly in which a concentrated light source, preferably, but not necessarily, of high intensity, directs a concentrated beam of light through a suitable glass filter or nest of filters and through an absorption cell containing the specimen fluid, the analysis of which is undergoing determination, the resultant transmitted light, following absorption, registering on a suitable photoelectric cell. The light source is water-jacketed, preferably both at the top and bottom, to maintain constant the temperature thereof throughout operation. By maintaining both the water jacket for the light source and the carrier for the light filters on a suitable frame common to them both and constructed of metal of high thermal conductivity, the filter carrier and hence the filters themselves are likewise maintained at constant operational temperature.

And now, having reference more particularly to the several views of the drawings, especially Figures 1 through 3, inclusive, it will be observed that I provide a flat frame member 10 here dis-

closed as rectangular and adapted in use to be disposed horizontally. It is constructed of brass, copper, aluminum or other suitable inexpensive metal of high heat conductivity. In the preferred embodiment it is carried on three or four supporting legs 11, from any suitable support member such as a table top or the like. Mounted in a suitable lamp socket 12, either of the screw or bayonet type, and here shown as a bayonet socket, I provide a suitable source of light 13. The socket 12 is carried in a collar 14 held down in the frame member 10 by suitable hold-down means such as screws 15. The lamp source 13 may be of any suitably concentrated type. The lamp 13 as shown is of the substantially point light source type, although it is within the province of my invention to employ what is known as a line-source lamp. It is of no particular moment which type is employed so long as the ultimate objective is achieved of having a concentrated source of scanning light, substantially uniform through the cross-sectional area of the projected light beam.

In the embodiment undergoing illustration I employ a General Electric concentrated filament lamp of 15 watt rating, operating normally at 2.5 amperes input on a 6-8 volt A. C. or D. C. service. This service is supplied through switch 16, series inserted in line 17 to plug 18.

In practice I surmount the lamp 13 by a suitable upper water jacket member 19. This assumes generally the form of a cylinder with axis transverse to that of the frame member 10, that is, it is normally disposed vertically, and is provided with annular cross-sectional detail to provide a channel for a cooling fluid circulating therethrough. At its bottom end it is outwardly skirted or flanged as at 19A, whereby it may be secured, with proper orientation, to the frame member 10 through the use of suitable hold-down means, later to be described. A window 20 of calibrated dimensions is provided through the vertical extent of the cylinder at a point adjacent the optical center 13A of the light source 13, and serves, when the water jacket 19 is properly orientated, to project a light beam of uniform area, with nearly parallel rays, towards the glass filters and the absorption cell containing the liquid undergoing analysis. It is necessary in this respect that the hold-down means employed for the water jacket 19 provide proper registry of the window 20 with respect to the other elements of the straight-line optical system. Such hold-down means comprise a plurality of apertures 21 let through the flange 19A, and corresponding threaded bores 22 in the frame member 10. Hold-down screws 23 serve to secure the water jacket 19 in its position of proper orientation.

It is further to be noted that water tubes 24 are fast at the bottom end of the water jacket 19, one such tube serving as an inlet for the cooling water and the other as the outlet thereof. Suitable recesses must of course be provided through the frame member 10 for the reception and passage of the water tubes 24. The location of these openings for the water tubes 24 will of course in itself determine the proper orientation of the water jacket 19.

The flow of cooling fluid through the water jacket 19 contributes effectively in the proper control of the operating temperature of light source 13. Variation in either the temperature of the cooling fluid or in the unit rate of flow thereof will contribute materially towards accurate control of the operating temperature of

the lamp 13. I find it advantageous, however, to provide still further sensitive temperature control means through the provision of a second cooling means disposed on the underside of the frame member 10, in the neighborhood of the base of the socket 12 of the lamp 13. Such additional cooling means is likewise disclosed more fully in the exploded perspective view comprising Figure 1.

This additional cooling means, indicated generally at 25, comprises a cylindrical portion 26 of comparatively slight depth, closed at its upper or head portion by a suitable web 27. This web 27 is centrally perforate at 28 for the reception of base 12 of the lamp 13, the central perforation 28 being flanked by marginal perforations 29 disposed concentrically thereabout and in registry with corresponding bores 30 in the frame member 10 for the reception of suitable hold-down means, such as bolts, nuts or the like. Outwardly extending water pipes 31, 31 serve for the inlet and outflow of cooling fluid which circulates through the hollow interior of the cylinder 26, the same being annular in cross-section. Thus, the lower cooling member 25 may be connected in parallel across the water supply to the upper cylinder 19. Not only does the cylinder 26 contribute appreciably to the cooling effect on the light source 13, but as well, it adds materially in maintaining the normal temperature of the frame member 10 and thus participates in maintaining cool the color filters later to be described.

Next to be described is the holder for the glass absorption cell and for the filter members. This holder, indicated generally at 32 in Figures 1 and 2, is constructed, in the present embodiment, of metal of comparatively high heat conductivity such for example as the same metal as that of which the frame member 10 is formed. In this manner heat is conducted with considerable rapidity from the filters to be described to the frame 10, and thence to the cooling jackets 19 and 25, so that optimum results are achieved.

The absorption cell 33, here shown of glass, but which obviously can be formed of other suitable transparent material, and which may be of any desired configuration, is here disclosed as an elongated member of generally rectangular section. A like configuration is imparted to the frame 32, so that, as is evident from Figure 1, a well 34 is provided therein, complementary in configuration to that of the cell 33. The frame 32 is provided at its side with a window 35 in axial registry with the window 20 in the water jacket 19. The holder 32 is secured to the frame member 10 in any desired suitable manner, in the present instance the holding means being shown as angle members 36 (see also Figure 2) of L section, extending along the transverse sides of the holder 32 and made fast thereto in any desired suitable manner, as by riveting, welding, or the like. The other web or leg 36A of the angle members 36 are made fast to the frame member 10 in desired suitable manner as by bolts or the like 37.

A rectangular frame is provided on the wide face 38 of the holder 32 disposed towards the light source 13. This frame, indicated generally at 39, is of metal and substantially follows the outline of the holder 32, the upper head 39A thereof, however, terminating short of the upper lip of the holder 32. Bolts, studs or similar retaining means 40 here shown as provided one in each corner of the rectangular frame 39, thread into

the latter and by means of a rectangular hold-down member 41 sleeved on the lock-down means 40, serve to secure rigidly into place one or more filter members 42 combined so as to provide properly for the particular wave length to be absorbed.

The cell 33 of course carries in it the solution, the analysis of which, through absorption phenomena, is undergoing determination. Provided rearwardly of the holder 32 and carried thereon is a photo-electric cell frame 43 (Figures 1 and 3) which lets into the frame 32 by means of a window 44 of nicely dimensioned opening. A photo-electric cell 45 of suitable conventional type is provided removably fast in the auxiliary frame 43, this photo-electric cell being retained in position by suitable screws or bolts for example. The photo-electric cell is connected with a conventional potentiometer or other suitable electrical balancing means by way of terminals 47 and nuts 46. Further details of this lock-down means are illustrated in Figure 2, the nuts 46 being paired with cooperating lock-down nuts 46'. The photo-electric cell of course is of conventional type, such for example, as the present-day General Electric photronic cell, well known in the art.

It is to be noted that the optical center of the filament 13A of the lamp 13, the axial center 20' of the window 20 of the water jacket 19, the optical centers 42' of the filters 42, the transverse geometrical center 33' of the absorption cell 33, the geometrical centers 35' and 44' of the windows 45 and 44, respectively, in the holders 34 and 43 and the optical center 45' of the photronic cell 45 are all disposed in the axial prolongation of each other, as indicated generally by the dotted line 48 in Figure 3. The total compass of the working parts of the colorimeter assembly as shown in Figure 3 is not in excess of five inches, while the over-all dimensions of the completed device as shown in Figures 1 and 2 is somewhat less than ten inches. The device is thus seen to be of small compass, neat and compact.

In use, the lamp 13 is energized through switch 16 from a suitable 6-8 volt A. C. or D. C. service through plug 18 and leads 17. As soon as the lamp is energized in the manner just described, the water jackets 18 and 25 are brought into operation and the cooling fluid circulated therein. This quickly brings the lamp 13 to standard operating temperature, the temperature being regulated as desired through control of either the temperature of the cooling water or the volume thereof, or both.

As has already been described, the additional function is served through the operation of the water jackets 19 and 25 of establishing equilibrium temperature conditions for the glass filters 42, 42'. Light from the lamp 13 is projected as a concentrated beam of determined cross-sectional area and comprised of substantially parallel unit columns or bundles of light rays, through the window 20 of the water jacket 19, and thence through the filters 42, which prevent the transmission of substantially all light except that of determined wave length. This wave length is determined in substantial accordance with the characteristic wave length of the element or elements, the concentration of which in the solution within the absorption cell 33 is undergoing determination. A reading is taken on the potentiometer for the condition in which no fluid is

present in the absorption cell 33. The size of the scanning field incident upon the cell 33 is determined by the dimensions of the window 35 in the holder 34, while the cross-sectional area of the beam incident upon the photronic cell 45 is determined by the dimensions of the window 44 in the sub-frame 43. After the initial or rest reading of the assembly is determined, the cell 33 is filled with the liquid containing the element, the concentration of which is to be determined, to a point above the upper level of the window 35' in the holder 34. A second reading is now taken, and the additional absorption of light which has been rectified to a given wave length by the filter 42, is the measure of the concentration of the absorbing element within the solution in the absorption cell 33.

The foregoing description of the operation of course has been simply generalized, and a more precise understanding will perhaps best attend upon the disclosure of the handling of a particular operational problem, such as confronts the industrial operator in everyday practice, in accordance with the teachings of my present invention:

It will at once be seen from the foregoing that the new construction is highly compact and self-contained, is of low first cost, gives rise to but little operational expense, and with properly determined control curves requires the attendance of an operator of but limited and routine skill. For a given specialized determination for which the individual installation is adapted, the assembly is quickly and sensitively suited so that accurate determinations can be achieved readily and with a minimum of delay. Shiftover to other uses can be readily achieved, but will involve some delay in selection and replacement of the filters 42, 42', in bringing these to proper operating temperatures and standardizing them at equilibrium values, and as well, in determining experimentally such control curves as may be required.

All these and many other highly practical advantages attend upon the practice of my invention. It is thus apparent from the foregoing that many embodiments of my basic inventive thought will readily occur to those skilled in the art upon consideration of the foregoing disclosure, all falling within the ambit of my invention, and that as well, many modifications of the present embodiment likewise will present themselves. Accordingly, I intend the foregoing disclosure to be considered as merely illustrative and not by way of limitation.

I claim as my invention:

1. Optical apparatus comprising in combination, a source of light, a filter system, a container for a solution the composition of which is to be determined, a frame of high heat conductivity on which said source, filter and container are mounted, and windowed water jacket means surrounding said source for cooling said frame and thereby maintaining constant the temperature of said filter and said solution container.

2. A colorimeter comprising in combination and in close registry with each other, a source of approximately parallel light rays, upper and lower water jacket cooling means disposed respectively at the top and bottom of said light source for isolating the heat of said light source.

3. A colorimeter comprising in combination, a frame member constructed of metal of high heat conductivity, a source of high intensity concen-

trated light carried on said frame member, a windowed water jacket cooling means carried on said frame member about said light source for maintaining constant the operating temperature of the light source and for projecting in desired direction a beam of light therefrom of determined cross-sectional area, a carrier for an absorption cell of high heat conductivity carried on and in thermally conductive relation to said frame member in the path of said projected light beam and in turn having mounted thereon a filter holder of high thermal conductivity, and a photo-electric cell mounted on said frame member in thermally conductive relation therewith and closely adjacent said absorption cell carrier and in the path of the beam of light transmitted through said filter members and the absorption cell holder.

4. A colorimeter, comprising in combination, a frame member constructed of metal of high heat conductivity, a source of high intensity, concentrated light carried on said frame member, a windowed water jacket cooling means carried on said frame member about said light source for normalizing and maintaining constant the operating temperature of the light source and for projecting in desired direction a beam of light therefrom of determined cross-sectional area, a carrier for an absorption cell of high heat conductivity carried on and in thermally conductive relation to said frame member in the path of said projected light beam and in turn having mounted thereon a filter holder of high thermal conductivity, a photo-electric cell mounted on said frame member in thermally conductive relation therewith and closely adjacent said absorption cell carrier and in the path of the beam of light transmitted through said filter members and the absorption cell holder, and a second water jacket cooling member disposed on the underside of said frame member, substantially in the axial prolongation of said light source, for abstracting heat from the lower side of said frame member, and thereby participating in the controlled cooling action.

5. Optical apparatus comprising, in combination, a source of light, a filter system, a frame of

high heat conductivity on which said source and filter are mounted, and windowed water jacket cooling means mounted on said frame in heat transfer relation therewith and surrounding said light source.

6. Optical apparatus comprising, in combination, a source of light, windowed water jacket cooling means surrounding said light source, and means conveying water to and from said jacket.

7. Optical apparatus comprising, in combination, a source of light, a frame of high heat conductivity on which said source is mounted, and windowed water jacket cooling means mounted on said frame in heat transfer relation therewith and surrounding said source for minimizing the transfer of heat from said source and cooling the frame.

8. Optical apparatus comprising, in combination, a source of light, a frame of high heat conductivity on which said source is mounted, windowed water jacket cooling means mounted on one side of said frame in heat transfer relation therewith and surrounding said source, and additional cooling means mounted on the opposite side of said frame in heat transfer relation therewith.

9. Optical apparatus comprising, in combination, a filter system, a frame of high heat conductivity on which said filter is mounted, and water jacket means mounted on said frame for removing heat therefrom and cooling said filter.
